[57] CLAIM

The ornamental design for a flatware handle, as shown and described.

DESCRIPTION

FIG. 1 is a front side elevational view of a flatware handle showing my new design and showing a knife blade in broken line, this broken line element is for illustrative purposes only and forms no part of the claimed design;

FIG. 2 is a right side elevational view of the flatware handle, showing a knife blade in broken line, this broken line element is for illustrative purposes only and forms no part of the claimed design;

FIG. 3 is a top plan view of the flatware handle, showing a knife blade in broken line, this broken line element is for illustrative purposes only and forms no part of the claimed design;

FIG. 4 is a bottom plan view of the flatware handle, showing a knife blade in broken line, this broken line element is for illustrative purposes only and forms no part of the claimed design; and,

FIG. 5 is a perspective view of the flatware handle, showing a knife blade in broken line, this broken line element is for illustrative purposes only and forms no part of the claimed design.

While a left side elevational view of the flatware handle is not shown in the drawings, it is to be understood that the left side elevational view of the flatware handle is identical to the right side elevational view of the flatware handle shown in FIG. 2.

While a rear side elevational view of the flatware handle is not shown in the drawings, it is to be understood that the rear side elevational view of the flatware handle is identical to the front side elevational view of the flatware handle shown in FIG. 1.
